TWO-TABLE NAILING-MACHINE.

1,251,913.

Specification of Letters Patent.

Patented Jan. 1, 1918.

Application filed May 28, 1915. Serial No. 30,984.

To all whom it may concern:

Be it known that I, ELMER C. NORTHRUP, a citizen of the United States, residing at San Francisco, in the county of San Francisco, State of California, have invented a new and useful Two-Table Nailing-Machine, of which the following is a specification, in such full and clear terms as will enable those skilled in the art to construct and use the same.

This invention relates to a box nailing machine and its object is to provide a machine which will be simple in construction and which will be easily operated by unskilled help to produce a box, two sides and one bottom being nailed at both ends in six operations.

This invention is intended to produce a machine which will nail both sides of the box on the ends on one portion thereof, while another portion of the machine will subsequently nail the bottom to both ends, the sides requiring four nailing operations, while the bottom requires two nailing operations, the two parts of the machine being combined with a feeding device which supplies the nail chucks with four sets of nails for the sides, following which another series of chucks are supplied with two sets of nails to complete the nailing of the bottom to the box.

An embodiment of the invention is shown in the drawing in which the same reference numeral is applied to the same portion throughout, and in which—

Figure 1 is a side elevation of the complete machine,

Fig. 2 is a front elevation of the complete machine,

Fig. 3 is a plan view of the slidable head carrying the nail chucks, the guides therefor being indicated in section,

Fig. 4 is a plan view of the lower portion of the machine, the upper portion thereof being cut away for purposes of illustration,

Fig. 5 is a side elevation of the cam used for feeding nails to the nail chucks,

Fig. 6 is a sectional view of the nail chuck and gage for the box end,

Fig. 7 is a development illustrating the operation of the cam shown in Fig. 5,

Fig. 8 is a plan view of the nail escapements showing the positions of the nails

with respect thereto at the time when the 55 nails are to be dropped into the chucks for nailing the bottom, said nails being dropped at the time the last nailing operation of the box is effected,

Fig. 9 is a side elevation of the bar carrying the nail escapements, a portion only being shown.

Fig. 10 is a plan view partly in section of the nail escapement and the nail chute adjacent the escapement,

Fig. 11 is a view of the nail escapement looking in a line parallel to the nail chute, and

Fig. 12 is a side elevation of one of the nail escapements shown in juxtaposition to 70 the end of one of the nail chutes.

The numeral 1 indicates the base of the machine from which base four posts 2, 3, 4, and 5 project, the posts 2 and 5 being joined at the top to form the main frame of the machine and carrying brackets 6, 7 which support the nail feeding chutes and the chutes leading to the nail chucks. The posts 2, 5 are formed with flanged guides on the edges thereof and carry respectively supporting 75 brackets 8, 9 through which the screws 10, 11 pass, said screws being adjusted by means of the hand wheels 12, 13 respectively. The screws 10, 11 support tables 14, 15 respectively, said tables having guides 16, 17, 18 85 and 19 to hold them in their proper position with respect to the posts 2 and 5.

Each of the tables 14, 15 is provided with a slotted angle plate 20, 21 respectively secured to the table by means of bolts 22 in 90 order to provide an abutment against which the box end may be placed to gage the proper position therefore when the side or bottom is to be nailed thereon.

The upper portion of the machine has inclined guides 23, 24 on which the cross head 25 is slidable. The cross head is provided with plates 26, 27 secured thereto by bolts for directing it in its proper motion on the guides 23, 24 and it has pins 28, 29 which 95 are connected with stirrups 30, 31 in turn connected to the driving links or rods 32, 33. The stirrups 30, 31 are slidable with respect to the links connected thereto by reason of the fact that springs 35, one for each of the 100 links 32, 33, are interposed between the ends of the links and the bottom of the stirrup, thereby allowing a certain movement of the

cross head with respect to said links and enabling the machine to make boxes of slightly different size without injury thereto when set in a given adjustment. The links 32, 33 are connected with crank pins 36, 37 at their lower ends, which crank pins are rotated by means of the shaft 38, said shaft being journaled in the posts 2 and 5.

The cross head 25 is provided with enlarged ends 38', 39, bored to receive rods 40, 41. The cross head has a groove in its underside, note Fig. 6, to receive heads 42 to which the nail driving punches 43 are connected. The rods 40, 41 are connected to lugs 45, 46, while the lower ends of said rods are connected to a cross bar 47 by means of lugs 48, 49 at the ends thereof. The cross bar 47 has a groove in its upper side to receive the heads of bolts 50, which bolts pass through lugs 51 carried by the upper end of the nail chucks 52, the object being to provide means whereby the nail chucks may be laterally adjusted. The cross bar 47 also supports a guide bar 53, said guide bar being carried by arms 54, 55 at the ends thereof, which arms are suitably bolted to the cross bar 47, the object being to position the box ends for nailing.

The lugs 45 and 46 each have an upwardly projecting member 57, each of which members rests upon a spring 58, (only one of said springs being shown) for the purpose of quickly releasing the chucks from the box when the nails have been driven thereinto. It will be understood that the chucks are placed at a distance of a quarter or three eighths of an inch above the box when the box is being made and that the nails are driven into the box from the chucks before the chucks actually touch the box, but not until the nail drivers come down into contact with the top of the box is the nailing completed and at that time the chucks have been forced down into contact with the box because the heads 42 depress the chucks into contact with the box, but as soon as the drivers begin to rise the two springs 58 lift the chucks off the box and enable the workmen to quickly shift it to effect the other nailing operations.

The front portions of the brackets 6, 7 support a cross bar 59, said cross bar in turn supporting the nail receiving hoppers 60, said hoppers being secured in a given position on said cross bar by means of clamps 61 and wing nuts 62, there being five clamps and wing nuts for the ten hoppers. Extending from the hoppers 60 downwardly are ten coiled steel spring tubes 63, said tubes being of such a length as to enable the chucks to move up and down into and out of engagement with the box without being disengaged from the chuck hoppers 60 into which they project at their lower ends. The frames 6, 7 also support a pivoted hopper 65, said

hopper having a notched bar 66 at its front end to permit the escape of nails after they have dropped into the slots 67 in its bottom to the plurality of nail chutes 68, there being one nail chute for each of the nail hoppers 60. The frames 6, 7 also support a cross bar 69 which is held normally to the left, Fig. 2, by means of a spiral spring 70, said spring being pushed to the right by means of the rotary ratchet cam 71.

The cam 71 is journaled on a stub shaft 72 secured to the frame 7 and it is operated by means of a bell crank lever having arms 73, 74, the latter arm having a link 75 connected with the pin 29, so that on each downward movement of the nail head the cam will advance one step and will push the bar 69 carrying the nail escapements 76 to the right such a distance as is necessary to discharge the proper number of nails in the proper tubes. The nail escapements comprise a steel block 78 having two springs 79, 80 secured thereto by screws, which springs assist in holding the L shaped nail escapement plates 81, 82 in their proper position, one of said plates passing under the end of the nail chutes 68 far enough to catch a fresh nail whenever necessary as indicated at 83. The nail escapements are adjusted on the bar 76 by means of the bolts 84, said bolts having wing nuts 85 which enable the nail escapements being adjusted from side to side whenever necessary to deliver the proper number of nails upon each throw of the bar 76.

It will be observed that in the development of the cam 71 which moves to the right, Fig. 7, that the bar 76 is now resting in a low place A of the cam and inasmuch as the box is supposed to have had its lower side nailed twice and upper side nailed once, the cam is ready to deliver a stroke of the greatest length in riding up over the cam portion B. The bar 76 then rides down into the cam portion C, but as at A it passes back far enough only to receive the nails for the five chucks at the right hand side of the machine. The cam on the next movement of the machine rides up on the high place D and completes the feeding of nails for the bottom, after which it falls down into the low place E the full depth of the cam, thereby picking up a nail for each escapement, but following the movement into the low place E it goes up on the high place F, which high place, however, is not high enough to deliver any but those nails in the first five chucks at the left of the machine, Fig. 2. Following the cam F are three deep depressions G, G¹ and G² alternated with three low cams H, H¹ and H², which after passing over the end of the bar are followed by the shallow depression A. The low cams H, H¹, H², serve to deliver the same series of nails as the

cam F, there being four nailing operations on one side of the machine to two nailing operations on the other side thereof.

The precise position of the several escapements and nails is illustrated in Fig. 8, in which it will be seen that the first five escapements on the right, Fig. 8, are in position to deliver a nail upon the next movement of the bar 76 over cam B, while the first five escapements at the left of the same figure are in such a position that the points of the escapements hold the nails and prevent them from being discharged on the following stroke. It will be understood that at this time the first five chucks at the left, Fig. 2 have previously had nails dropped therein and are ready to complete the nailing of the box side.

The machine is driven from a belt pulley 88 carried on the shaft 89, which shaft is supported in journal boxes of the posts 3 and 4. Above the shaft 89 there are shafts 90, 91 and 92, the shaft 91 being supported in journal boxes in said posts 3, 4, while the shaft 90 is a short shaft supported in a journal box of the post 3 and the shaft 92 is a short shaft supported in a journal box of the post 4. The shaft 89 carries a gear 93 in mesh with a larger gear 94 on the shaft 90, said shaft also having a gear 95 in mesh with a larger gear 96 on the shaft 91, while the latter shaft carries a small gear 97 in mesh with a larger gear 98 on the shaft 92, the object being to rotate the gear 98 slowly so as to raise and lower the rod 99 pivoted to the gear 98 by the pin 100 and pivoted at its upper end to the nail box 65, the object being to roll the nails around in the nail box to work them into the feeding slots carried thereby.

The pulley 88 has a clutch flange 101 which coöperates with the slideable clutch member 102 to drive the shaft 89 when engaged by the operator. The slideable clutch member is forced into engagement with the flange of the pulley by means of a heavy spiral spring 103 which bears on a washer 104 held in a fixed relation to the shaft by means of the pin 105. The clutch member is shifted by means of the forked lever 106 pivoted on a bracket 107 secured on the base of the machine. This forked lever has an arm 108 which is engaged by means of a roller 109 on a lever 110 also pivoted on the bracket 107 but in front of the pivot point of the lever 106. The lever 110 has a roller 111 thereon which is engaged by the cam 112 when it is necessary to stop the machine, as it is on each revolution of the cam shaft.

The cam 112 is so set that it will pass beyond the roller 111 far enough to allow the operator to disengage the roller 109 from the arm 108 to allow the slideable clutch member to engage the flange on the

pulley 88 when the operator steps on the foot pedal 114, said foot pedal being carried by a shaft 115 journaled in lugs 116, 117 on the base of the machine. The shaft 115 also has an arm 118 which is connected at its upper end to the link 119, which link is connected to the lever 110 and thereby enables the workman to start the machine.

After the clutch members have been engaged the shaft 88 will begin to rotate and will turn precisely one revolution, whereupon the cam 112 will engage the roller 111 and will throw the slideable clutch member out of engagement with the running member and at the same time the brake lever 120 pivoted near the lower end of the post 3 at 121 will be forced over into engagement with a wheel 122 on the shaft 89. The brake lever has an arm 123 loosely connected therewith by means of the bolt 124 and spiral spring 125, the position and pressure of which determines the suddenness with which the shaft 89 will be stopped. The forward end of the lever 123 has a roller 127 thereon which is engaged by the shoulder of a crank 128, which crank carries the pin 36'. The roller 109 is held normally against the arm 108 by means of the spiral spring 130. The brake lever is prevented from moving too far away from the wheel 122 by means of a lug 131 on its lower end.

The operation of the machine is as follows: The workman first places a box side on the table 15, he then places a box end thereon and nails the upper side thereto, another end may then be placed adjacent the chuck and the side that has been nailed turned end for end, whereupon the second end is nailed thereto. As soon as the two ends have been nailed to the side, the side that has been placed on the table may be picked up with the two ends and in two operations of the machine it will be nailed to the two ends. During the last operation of nailing the sides five nails will be delivered to the five right hand chucks, Fig. 2, and upon the next movement of the foot lever the bottom will be nailed to the box, after which the box may be reversed and the bottom is nailed to the other end, whereupon the cycle of operations is repeated with other box ends, sides and bottoms indefinitely.

It is to be noted that the inclined position of the nail chucks is such with respect to the table on which the nailing is done that when the sides and bottoms of boxes have been nailed on that the nails all incline in different directions. The object of this is to produce a stronger box than would be the case if the nails were all driven in at right angles to planes of the sides and bottom. The result of driving the nails in this manner is that to remove any side or bottom it is necessary to bend the nails.

Having thus described my invention what I claim as new and desire to secure by Letters Patent of the United States, is as follows, modifications within the scope of the 5 claims being expressly reserved:

1. A box nailing machine comprising a frame, two adjustable tables carried thereby, sets of chucks for the tables, the set of chucks for each table being alined at the back of 10 the tables, chutes leading to said chucks, means to feed nails into said chutes, a cam to deliver two series of nails in one set of said chucks over one table and then to deliver a series of nails for a set of chucks 15 over the second table, and means to drive the nails after they have been fed to the chucks.

2. A box nailing machine comprising a frame, two adjustable tables carried thereby, 20 sets of chucks for the tables, the set of chucks for each table being alined at the back of the tables, chutes leading to the chucks, means to feed nails into said chucks, a cam to deliver two series of nails in the 25 chucks over one table and then to deliver a series of nails in the chucks over the other table, and means to operate nail drivers in all of the chucks on each operation of the machine.

3. A box nailing machine comprising a frame, two adjustable tables carried thereby, chucks for each table, the set of chucks for each table being alined at the back of the 30 tables, nail chutes leading to each chuck, a nail escapement for each nail chute, a cam to move said escapement to deliver two series of nails to the chucks over one table and then to deliver series of nails to the chucks over the other table, and means to 35 drive the nails after they have been fed to the chucks.

4. A box nailing machine comprising a frame, two adjustable tables carried thereby, side by side, nail chucks over each of the 40 tables, a gage adjacent the nail chucks for determining the position of the box shocks, means to feed two series of nails to the 45

chucks over one of the tables and then to deliver series of nails to the chucks over the other table, a nail driver for each of the 50 chucks, a slideable supporting arm for the nail drivers, and means to move said nail drivers, said means moving in a plane substantially parallel to the line of motion of the nail drivers.

5. A box nailing machine comprising a frame, two adjustable tables carried thereby, sets of chucks for the tables, a movable frame supporting said chucks, chutes leading to said chucks, means to feed nails into said 60 chutes, a cam to deliver two series of nails in one set of chucks over one table and then to deliver a series of nails for the chucks over the second table, a nail driver for each chuck, means to resiliently support the frame 65 carrying the nail chucks, and resilient means for moving the head carrying the nail drivers.

6. A box nailing machine comprising a frame, box supporting tables carried thereby, two series of nail driving chucks carried by a movable frame, resilient supports for the frame carrying said chucks, means to drive the nails fed to the chucks into a box placed on the support, said means forcing 75 the chucks into contact with the box, the resilient supports for the chuck holding frame lifting the chucks off the box immediately after the completion of the nailing operation and before the nail drivers have 80 returned to the end of their throw, and a cam for feeding two series of nails to one set of nail driving chucks and a single series of nails to the other set of nail driving chucks.

In testimony whereof I have hereunto set my hand this 18th day of May, A. D. 1915, in the presence of the two subscribed witnesses.

ELMER C. NORTHRUP.
